UNITED STATES PATENT OFFICE

SILAS M. FORD, OF ST. PAUL, MINNESOTA.

MACHINE FOR MAKING LATH-BOARD.

1,258,328.

Specification of Letters Patent.

Patented Mar. 5, 1918.

Original application filed May 8, 1916, Serial No. 96,259. Divided and this application filed September 18, 1916. Serial No. 120,703.

To all whom it may concern:

Be it known that I, SILAS M. FORD, a citizen of the United States, and a resident of St. Paul, in the county of Ramsey and State of Minnesota, have invented certain new and useful Improvements in Machines for Making Lath-Board, of which the following is a specification.

This invention relates particularly to a machine for making lath-board wherein the lath-board, preferably of water-proofed fibrous material, is crimped into a corrugated or dove-tailed shape, and means are also provided for running a stiffening wire through the crimped stock, and is a divisional of my copending application, Serial #96,259, filed May 8th, 1916 and bearing the same title.

One object of my invention is to provide in a machine for crimping material into a corrugated or a dove-tailed shape, means for pressing the corrugations more tightly together and maintain them in this relation as they progress through the machine.

Another object of my invention is to provide oscillatory means for pressing corrugations or plates formed in the machine into more intimate relations with each other and maintain them in this relation as they pass through the machine.

Another object of my invention is to provide an oscillatory member that will strike alternately the two edges of plaits formed by the machine on alternate cycles of the oscillation of the member.

With these and incidental objects in view, the invention consists of certain novel features of construction and combination of parts, the essential elements of which are hereinafter described with reference to the drawings which accompany and form a part of this specification.

Figure 1 is a side elevation of my improved machine, and Fig. 2 is a plan view of the same. Fig. 3 is an enlarged sectional view showing the pivoted guides used for the reinforcing wires, and Fig. 4 is a plan view of the same.

The water-proofed paper or whatever material is to be used in making the lath-board, is taken from the roll 1, Fig. 1 in which it is ordinarily shipped.

The paper 3 passes through the guides 4 of the crimping rolls 5 and 6, which are geared together and driven by any suitable means, and cleats 7 crimp the paper into a corrugated shape, as plainly shown in Fig. 1.

I preferably use guides for the removal of the paper from the corrugating rolls as described in my copending application heretofore referred to, and as their action is similar they will not be further described in this specification.

I utilize a pair of rocker bars 33', Fig. 1, driven by connecting rods 34 from the pinions 35, which in turn are driven by gears carried by the rolls 5 and 6 to form the rectangular corrugations into dovetailed corrugations.

The resultant oscillatory motion is timed through the gearing, so that when the face 36 travels in an anti-clockwise direction, it will strike points 37 of the corrugated paper and press it downwardly, while the face 38, 75 also traveling in an anti-clockwise direction, will strike points 39 of the corrugated paper and force these portions of the paper upwardly.

On the return stroke of the oscillatory motion, the surface 36 will strike points 40, while traveling in a clockwise direction, and the face 38 will strike points 41, also while traveling in a clockwise direction, so that by the action of the rocker arms, the corrugated shape is forced into the dove-tailed shape, shown at 42.

I prefer to use with this method a pair of squeeze rolls 48, although they are not absolutely essential.

With this construction I utilize a pair of threading rollers 44 having slats 45 thereon so spaced, and the rolls so geared that these slats will register with the spaces between the surfaces 9 of the dove-tailed paper. 95 These slats have slots to receive and support the reinforcing wires 26 and they are threaded through the webs 10 of the corrugated lath-board at this point to stiffen and reinforce the lath-board.

For guiding the wires 26 I provide a series of pivoted and slotted guides 47, Figs. 3 and 4, suitably mounted on the frame of the machine.

These guides 47 are pivoted at 48, so that they are normally in the position of the ones shown on the standard 50, Fig. 3, but when the corrugated paper passes over them, 5 the forward end is cammed by the paper itself, and they assume the position of the ones shown on the standard 49, Fig. 3. As the wires 26 lie in the slots of the guides 47 in the position shown on the standard 49, 10 they are prevented from bending sidewise from the strain set up by forcing the paper onto the wires, and as the dove-tailed paper with the wires therein reach the guides and force them into the position shown on the 15 standard 50, the paper with the wires threaded through rides easily over the pivoted guides and they disappear below the surface of the lath like faces of the paper, and the slots are thereby disengaged with 20 the wires which at this time are firmly reinforced by the paper through which the wires have been forced.

With the construction shown in Figs. 1, 2, 3 and 4, the guide wires would pass through 25 the rolls and slats used in the forming of the dove-tailed lath-board, and the threading means in the same manner as already described in my copending application aforesaid.

30 With the construction as shown, the guides 4 run entirely through the forming and threading portion of the machine, and I prefer to have the guides narrowed at the points in the forming machine where the 35 forming of the lath-board is changed from a corrugated to a dove-tailed shape, so that while the lath-board fits the guides closely in its corrugated shape, it will also fit the narrowed guides closely in its dove-tailed 40 shape.

While I have described my invention and illustrated it in one particular design, I do not wish it understood that I limit myself 45 to this construction, as it is evident that the application of my invention may be varied in many ways within the scope of the following claims:

1. In a machine for making lath-board, 50 the combination of a pair of corrugating rolls whereby material may be formed into a corrugated shape, a pair of rocker bars associated therewith, and means for oscillating said rocker bars so that the sides of the corrugated form may be struck alternately 55 thereby, thus forcing said corrugated shape formed by said rolls into a dove-tailed shape.

2. In a machine for making lath-board, 60 the combination of a pair of corrugating rolls whereby material may be formed into a corrugated shape, a pair of rocker bars associated therewith, means for oscillating said rocker bars so that the sides of the corrugated form may be struck alternately

thereby, thus forcing said corrugated shapes 65 formed by said rolls into a dove-tailed shape and squeeze rolls associated therewith for squeezing said dove-tailed forms to the desired thickness.

3. In a machine for making lath-board, 70 the combination of a pair of corrugating rolls, a pair of rocker bars associated therewith and timed with said rolls so that one of said rocker bars will strike the forward and rearward edge of each of the faces of 75 one side of the corrugated material at the same time that the other of said bars strikes the rearward and forward edges of the other of said sets of faces respectively.

4. In a machine for making lath-board, 80 the combination of a pair of corrugating rolls, a pair of rocker bars associated therewith, a pair of squeeze rolls, stripper guides for carrying the material from said corrugating rolls through said rocker bars and 85 said squeeze rolls, said stripper guides being narrowed where they pass through said rocker bars.

5. In a machine for making lath-board, 90 the combination of a pair of corrugating rolls, a pair of rocker bars associated therewith, and a stripper guide for carrying the material from said corrugating rolls through 95 said rocker bars, the space in said guide through which said material passes being narrowed where said guide passes through said rocker bars.

6. In a machine for making lath-board, 100 the combination of a pair of corrugating rolls, a pair of rocker bars, a pair of squeeze 105 rolls, a stripper guide for carrying the material from said corrugating rolls through said rocker bars and said squeeze rolls, said stripper guide being narrowed where it passes through said rocker bars, and narrowed still further where it passes through 110 said squeeze rolls.

7. In a machine for making lath-board, 110 the combination of means for forming material into a corrugated shape, means for threading a reinforcing wire through the webs of said corrugated shape and a pivoted 115 reinforcing guide for said wire for guiding and reinforcing said wire until the material is threaded thereon.

8. In a machine for making lath-board, 120 the combination of means for forming material into a corrugated shape, means for threading a reinforcing wire through the webs of said corrugated shapes and a pivoted reinforcing guide for said wire for guiding and reinforcing said wire until the material is threaded thereon, but adapted to be swung from said wire by said material as said material is threaded onto said wire. 125

9. In a machine for making lath-board, 130 means for forming material into a dove-tailed shape, means for threading reinforce-

ing wires through the webs of said dove-tailed shapes, and a series of pivoted reinforcing guides for each wire.

10. In a machine for making lath-board, means for forming material into a dove-tailed shape, means for threading reinforcing wires through the webs of said dove-

tailed shape, and a series of pivoted reinforcing guides for each wire, said guides being adapted to be successively swung 10 from said wires as said material reaches said guides.

SILAS M. FORD.
